ATTY.

UNITED STATES PATENT OFFICE

HARRY V. BALL, OF CONCORD, MASSACHUSETTS, ASSIGNOR TO R. HOE & CO., INC., OF NEW YORK, N. Y., A CORPORATION OF NEW YORK

WEB LEAD FOR PRINTING MACHINES

Application filed August 20, 1931. Serial No. 558,389.

This invention relates to web leads for printing machines, having for its primary object to provide means whereby in multi-unit printing presses the paper rolls may be 5 made to expire at approximately the same time, thus obviating the loss of many papers as is now occasioned when it becomes necessary to introduce new rolls of paper to the printing units.

10 A further object of the invention is to provide means associated with a multi-unit printing machine whereby when it becomes necessary to make a roll change, only one stop of the machinery is necessary, whereby 15 in addition to the saving of waste papers, economy of running time is obtained.

With these objects in view, together with others which will appear as the description proceeds, the invention consists in the novel 20 construction, combination and arrangements of parts, all as will be described more fully hereinafter, illustrated in the drawings and particularly pointed out in the claims.

In the drawings:

25 Fig. 1 is a diagrammatic side elevation of a conventional form of multi-unit printing press and illustrating the application thereto of mechanism involving the invention,

30 Fig. 2 is an edge view of papers delivered from the press as constituted in Fig. 1, and disclosing the relative positions of the joints of paper delivered from the three printing units,

35 Fig. 3 is a perspective view of a portion of a folded paper delivered from the press and illustrating the location of some of the paper joints, and

40 Fig. 4 is a similar view disclosing the location of other points of connection of the paper webs.

It will be understood that in printing presses when a paper roll expires it becomes necessary to either stop or materially slow down the press so that a new roll may be 45 swung into position and its exposed end pasted to the end of the expiring roll, to produce a continuity of web. When this occurs, the printed paper having the pasted seam of the connected webs is discarded 50 for obvious reasons, and it is at once ap-

parent that in instances where a number of paper rolls are employed, such as in multi-unit presses, the waste of printed papers is material, because of the fact that the paper rolls do not all expire at the same time. Not 55 only is this loss objectionable from the standpoint of discarded papers, but also in the loss of time incident to the more frequent slowing down or stopping of the press in order that the web connections may be effected. 60

The present invention seeks to overcome the objections noted, and while the present disclosure is but one preferred embodiment of the invention, I am aware that the same general results may be accomplished by resorting to mechanism or means differing from that herein disclosed.

Referring now to the drawings, the press diagrammatically shown includes three printing units which are designated A, B and C respectively, each of which is supplied with paper taken from the rolls D, E and F mounted beneath or in close proximity to their respective printing units. The webs of paper 5, 6 and 7 pass from the several printing units and are led to a folder G of conventional form arranged near one end of the press frame.

The paper rolls for the several printing units are arranged immediately adjacent thereto, and the distances from these rolls to the printing units are approximately the same. However, as the printing units themselves vary in their distances from the folder G, it becomes necessary to provide means whereby 80 the run of web from each printing unit to the folder will be substantially the same. In accomplishing this result, the unit A, which is farthest removed from the folder, has its web 85 passing to the folder in substantially a straight line, rollers or guides 8 being employed in the proper conveyance of this web. As the printing unit B is somewhat nearer to the folder than the unit A, it becomes necessary to elongate the web run from this printing unit to the folder in order that the said web run may correspond substantially 90 with that of the unit A. In accomplishing this, guide rolls 9 are arranged above the printing unit B and between the latter and the 95 folder. The web 100

folder in such manner that the web will pass from the unit toward the folder and then will double back toward the printing unit again and then forwardly in substantially a direct line to the folder; the distortion shown making the web run from the unit B to the folder G substantially equal to that between the unit A and the said folder. As the unit C is more closely associated with the folder than either of the printing units A and B, it becomes necessary to elongate or increase the path of travel of the web leading from the said unit C to the folder, and this is accomplished by arranging the guide rolls 10 substantially as shown; the web 7 upon leaving the unit C passing first rearwardly in the direction of unit B, then forwardly in a straight line toward the folder, then doubling back in the direction of the unit C, and then 20 passing over suitable guides for delivery to the folder.

By arranging the several guide rolls for the respective printing units in the manner disclosed, the webs passing thereover will be 25 all of the same or substantially equal length, and it will be understood that where paper rolls of substantially identical size are used, the same will expire at approximately the same time. Upon expiration of a roll, the 30 roll holders are swung so as to bring the new rolls into position, whereupon the end of the new roll for each printing unit is pasted to the tail end of the expiring web and the operation of the press proceeds. The doubled or 35 pasted ends of the several webs will therefore occur at substantially the same point in a folded paper, so that it will be necessary only to discard those folded papers containing the adhered portions. As this occurs in only 40 one or two folded papers, the loss of completed papers is decidedly few.

Fig. 2 shows the relative positions of the joints in the three webs 5, 6 and 7 as delivered from the printing units. It will be 45 noted that these joints are slightly staggered, which is desirable, in order to avoid running an excessive thickness of paper through the cutting or folding mechanism which would occur if the joints corresponded exactly. The 50 arrangement is such, however, that the three joints all occur within the length of two papers lengthwise of the web, of which one is shown in Fig. 3 and the other in Fig. 4. In Fig. 2, the spaces between the arrow heads at 55 11 and 12 indicates the length of successive pages, while the dotted lines 13 and 14 represent the lines of fold of these pages. It is 60 apparent, therefore that when cut apart and folded upon the lines 13 and 14, the web joints in the folded paper will occur approximately as is represented in Figs. 3 and 4, in a staggered relation so as not to subject the cutting and folding mechanism to an excessive paper thickness.

65 From the foregoing it is apparent that a

press equipped with means such as employed for equalizing the web runs from the several printing mechanisms to the folder, the objects set forth will have been accomplished, and while the foregoing is a description of the invention in its preferred embodiment, I am nevertheless aware that variations in this structure and specific means may be resorted to for the accomplishment of similar results without departing from the spirit of my invention. 75

Having thus described my invention, I claim:—

1. In a printing press, the combination with a pair of printing units and a folder; of means interposed between said folder and one of said units whereby a web traveling therethrough will be of the same length as a web from the other unit to said folder. 80

2. In a printing press, the combination with a plurality of printing units and a folder; of means interposed between said folder and each unit whereby the web run between all of said units and said folder will be equal. 85

3. In a printing press, a folder, a plurality of printing units disposed at varying distances from said folder, and means interposed between said folder and said units whereby web runs therebetween will be substantially equal. 90

4. In a printing press, a frame, a folder on said frame, a plurality of printing units on said frame arranged at varying distances from said folder, a series of web guides interposed between each unit and said folder, said guides arranged so that the web length between each unit and said folder will be substantially equal. 95

5. In a printing press, a frame, a folder on said frame, a plurality of printing units on said frame disposed at varying distances from said folder, and series of web guides on said frame corresponding in number to the number of said units; said series so arranged that webs passing from said units over their respective guide series will be of substantially equal length. 100

6. In a printing press, a frame, a folder at one end of said frame, a plurality of printing units on said frame located at varying distances from said folder, and series of guide rolls corresponding in number to said units supported by said frame; the rolls of each series being so arranged that webs passing over the same from their respective units to said folder will be of substantially equal length. 115

7. In a printing press, the combination with a pair of paper rolls and a folder; of means interposed between said folder and rolls whereby the webs traveling therethrough to the folder will be of equal length. 120

8. In a printing press, the combination with a plurality of paper rolls and a folder, of means interposed between said folder and 130

each roll whereby the web run between all of said rolls and said folder will be equal.

9. In a printing press, the combination with a folder and a plurality of paper rolls arranged at varying distances from the folder, of a series of web guides interposed between each roll and said folder, said guides arranged so that the web length between each roll and said folder will be substantially equal.

In testimony whereof, I affix my signature.
HARRY V. BALL.
